UNITED STATES PATENT OFFICE.

GEORGE S. LEWIS, OF SPRINGFIELD, MASSACHUSETTS, ASSIGNOR TO J. STEVENS ARMS & TOOL COMPANY, OF CHICOPEE FALLS, MASSACHUSETTS, A CORPORATION OF MASSACHUSETTS.

FIREARM.

1,059,477.

Specification of Letters Patent.

Patented Apr. 22, 1913.

Application filed November 23, 1912. Serial No. 733,043.

To all whom it may concern:

Be it known that I, GEORGE S. LEWIS, a citizen of the United States, residing in Springfield, Hampden county, State of Massachusetts, have invented certain new and useful Improvements in Firearms, of which the following is a specification, reference being had to the accompanying drawing, which forms a part hereof.

10 This invention relates to breech-loading firearms, and especially to single-shot rifles of low cost, in which the barrel is fixed with respect to the frame and the breech-block is movable.

15 The principal object of the invention is to provide a very simple and yet strong breech mechanism and in accordance with this part of the invention the operating lever is itself hung directly upon the pivoted 20 breech-block and coöperates directly therewith.

A further object of the invention is to facilitate the placing of the main spring in position.

25 The invention will be more fully explained hereinafter with reference to the accompanying drawing in which it is illustrated and in which—

Figure 1 is a view partly in side elevation 30 and partly in longitudinal section of so much of a firearm as is necessary to enable the invention to be understood, the breech-block being shown in the closed position with the hammer down. Fig. 2 is a view 35 similar to Fig. 1 but showing the breech-block in its open position, with the hammer cocked.

In the embodiment of the invention illustrated in the drawing the stock *a* has secured 40 thereto as usual the frame *b* which receives the barrel *c*. In the frame is mounted a breech-block *d* which is pivoted as at *d'* and may be provided as usual with a spring plunger *d''* to actuate the usual extractor *e*. 45 The breech-block *d* is substantially L-shaped and carries the firing pin, indicated by dotted lines at *d''*, as usual. At the rear end of the breech-block, as at *d''*, is pivoted the operating lever *f* which also forms the trigger guard. This lever is notched on its 50 rear side, as at *f'*, to engage a pin *g* which is fixed in the frame and may be provided with a loose sleeve *g'*. This pin *g*, as will be observed, is placed forward of the vertical 55 plane which passes through the pivot *d'*

on which the lever is hung directly to the breech-block and the upper shoulder *f''* of the notch *f'* is squared or otherwise formed so that the radial distance of the outer portion of the shoulder is slightly greater than 60 that of the inner portion of the shoulder. The lever *f* is also provided with a shoulder *f'''* for coöperation with the breech-block. The rear face of the breech-block is arranged to bear against the face of the hammer *h*, 65 so that the hammer is cocked when the breech-block is moved to its lower position, as shown in Fig. 2 and the hammer is retained in its cocked position by the combined sear and trigger *i* as usual, against the pressure of the main spring *k*. The latter is formed so that it can be placed in position readily and to that end the plunger, surrounded by the spring itself, is made in two parts *k'* and *k''* which telescope, the one 70 within the other, as clearly shown in Fig. 2, each part being formed with a shoulder *k'''* *k''''* for the corresponding end of the spring *k*. The telescoping plunger and the spring can be assembled outside of the receiver and readily slipped into place when the parts of the gun are being assembled. 75

In the operation of the breech mechanism shown in the drawing, when the parts are 80 in the closed position, as shown in Fig. 1, and the breech is to be opened, the lever is pressed downwardly and forwardly. Some little effort is required to start the lever by reason of the bearing of the shoulder *f''* 85 against the pin *g*, but after the movement is commenced the shoulder *f'''* of the lever bears against the underside of the breech-block so that in the continued forward and downward movement of the lever the breech-block is swung downwardly from its closed 90 position, shown in Fig. 1, to its open position, shown in Fig. 2. During this movement the hammer is cocked by the breech-block and the extractor is operated. When the breech is to be closed the lever is pulled 95 rearwardly and upwardly. In the first part of its movement the rear face of the lever, above the shoulder *f''*, bears upon the pin *g*, swinging and sliding upwardly thereon, thereby causing the breech-block to be returned to its closed position. When the limit of movement is approached, the shoulder *f''* snaps over the pin and thereby locks 100 the lever and the breech-block in the firing position. Since the pin *g* is forward of the 105 110

vertical plane of the pivot d^4 it will be seen that through the action of the lever, when the shoulder f^2 snaps over the pin g , the breech-block is crowded upwardly and rearwardly so that all lost motion, due to looseness of fit or wear on either or both of the pins d' and d^4 , is taken up and there is no lost motion to be taken up when the cartridge is exploded.

10 It will be understood that the form and relation of the parts may be varied to suit different conditions of use and that the invention is not restricted to the precise construction shown and described herein.

15 I claim as my invention:—

In a breech-loading firearm, the combination of a frame, a breech-block pivoted in

the frame, and an operating lever hung directly upon the breech-block, the lever having a notch in its rear side and the frame having a fixed pin for coöperation with the notched lever, said pin standing forward of the vertical plane of the pivotal connection between the breech-block and the lever whereby the breech-block is forced home positively when the lever is moved to closed position.

This specification signed and witnessed this 20th day of November A. D., 1912.

GEORGE S. LEWIS.

Signed in the presence of—

ALBERT F. CROWTHER,
CHARLES R. LOVELAND.
